PORTABLE 8-TRACK STEREO TAPE PLAYER

Richard E. Lee, Cazenovia, and Richard Calbertson,
Manlius, N.Y., assignors to General Electric Company

Continuation-in-part of abandoned design application Ser.
No. 413,520, Nov. 7, 1973. This application Apr. 1,
1974, Ser. No. 456,932

Term of patent 14 years

Int. Cl. D14—01, 03
U.S. Cl. D26—14 B

FIG. 1

FIG.2

FIG.3

FIG.4

FIG.5

FIG.6

FIG. 1 is a front elevation view of a portable 8-track stereo tape player, shown in closed condition, in accordance with our design;

FIG. 2 is a rear elevation view of the player, in closed condition;

FIG. 3 is a left side elevation view of the player, in closed condition;

FIG. 4 is a right side elevation view of the player, in closed condition;

FIG. 5 is a top plan view of the player, in closed condition;

FIG. 6 is a bottom plan view of the player, in closed condition;

FIG. 7 is a front and rear, right side, and top perspective view of the player, in opened condition; and

FIG. 8 is a rear elevation view of the player, shown in opened condition.

This is a continuation-in-part of design application Ser. No. 413,520, filed Nov. 7, 1973, and now abandoned.

We claim:

The ornamental design for a portable 8-track stereo tape player, as shown and described.
